UNITED STATES PATENT OFFICE.

WASHINGTON H. KILBOURN, OF GREENFIELD, MASSACHUSETTS.

THIRD-RAIL SYSTEM FOR ELECTRIC RAILWAYS.

SPECIFICATION forming part of Letters Patent No. 764,244, dated July 5, 1904.

Application filed October 1, 1903. Serial No. 175,276. (No model.)

To all whom it may concern:

Be it known that I, WASHINGTON H. KILBOURN, of Greenfield, in the county of Franklin and State of Massachusetts, have invented 5 certain new and useful Improvements in Third-Rail Systems for Electric Railways, of which the following is a specification.

This invention relates to third-rail conductor systems for electric railways, and has for 10 its object to reduce the expense attending the installation and maintenance of such conductors, at the same time making the same entirely safe and free from danger.

To these ends the invention consists in the 15 improvements which I will now proceed to describe and claim.

Of the accompanying drawings, forming a part of this specification, Figure 1 represents a top plan view of a portion of a street-railway track embodying my invention. Fig. 2 represents a longitudinal section on line 2 2 of Fig. 1. Fig. 3 represents a transverse section. Fig. 4 represents an enlargement of a portion of Fig. 2.

25 The same letters of reference indicate the same parts in all the figures.

In the drawings, *a a* represent the track-rails of an electric railway, the same being supported in any suitable way, preferably by 30 wooden ties *b*.

c represents a continuous conductor for the electric current, said conductor being preferably a rigid rail or bar, and may therefore be called a "third" rail. The conductor may, 35 however, be a flexible wire, mounted on suitable supports.

d d represent guard-rails which are supported at opposite sides of the conductor *c* and project above the same. The upper edges of 40 the guard-rails *d d* are separated from each other by a narrow slot *d'*, which is formed to receive a conducting-arm mounted on the car and in movable contact with the conductor *c*. The upper edges of the guard-rails are prefer- 45 ably on about the same level as the tread-surfaces of the rails *a*, the conductor *c* being below the level of the upper edges of the guard-rails. The conductor *c* is mounted on supports *c'*, which are preferably affixed to 50 the ties *b*. When the usual filling and pav-

ing material, which is not shown in the drawings, is in place, it occupies the spaces between the rails *a* and the guard-rails *d*, the latter supporting said material and preventing it from encroaching upon the space in 55 which the conductor *c* is located.

The guard-rails *d* are composed of relatively short sections 2 2, as shown in Fig. 1, the sections being suitably insulated from each other and from the conductor *c*. The length of the 60 sections 2 is such that when any section is electrically energized by the conducting-arm on the car, the latter receiving the current from the conductor *c*, the energized section will not project far enough from either end 65 of the car to constitute a source of danger.

f represents a conducting arm or shoe which is connected with a car and has a suitable electrical connection with the motor on the car. The shoe *f* is formed to enter the slot *d'* and 70 ride upon the conductor *c* and is provided with shoulders *f' f'*, which may bear upon the upper edges of the guard-rails at opposite sides of the slot *d'*, so that the wear of the shoe is supported in part by the guard-rail. 75 The shoe *f* may be adjustably connected with the car by means of swinging links *g g* or otherwise, so that it may be raised and lowered.

It will be seen that the guard-rails arranged 80 to cover and protect the continuous conductor and composed of insulated sections enable a third-rail conductor to be used with entire safety, the system being of relatively inexpensive construction. By mounting the guard- 85 rails and the continuous conductor on the ties I prevent liability of the accumulation of water around the conductor, any water which may find its way into the space between the guard-rails readily subsiding through the 90 loose material between and under the ties.

I claim—

1. A third-rail conductor system comprising a conductor and guard-rails secured at opposite sides of and projecting above said conductor, and separated from each other above the conductor by an arm-receiving slot, said guard-rails being composed of sections insulated from each other, and from the conductor. 95

2. A third-rail conductor system comprising a conductor located between the track-rails and below their tread-surfaces, and guard-rails secured at opposite sides of and projecting above said conductor and separated from each other above the conductor by an arm-receiving slot, the guard-rails being composed of sections insulated from each other and from the conductor, and a conducting-shoe

formed to enter said slot and bear on the conductor, said shoe having shoulders formed to bear on the guard-rails. ¹⁰

In testimony whereof I have affixed my signature in presence of two witnesses.

WASHINGTON H. KILBOURN.
